Josiah T. Buck
Letters Patent

The schedule referred to in these Letters Patent and making part of the same containing a description in the words of the said Josiah T. Buck himself of his improvement in the art of cutting the uppers of Boots, Booties and high laced shoes.

To all to whom these presents shall come. Be it known that I Josiah T. Buck of New Canaan in the County of Fairfield and State of Connecticut have invented a new and useful art or improvement in cutting uppers for Boots, Booties and high laced shoes and that the following is a full and exact description thereof. To ascertain the size of the foot and leg the measure is taken as is now the practice. the measure is then laid on the leather or cloth on which the boot or shoe is intended to be cut from and designed to be cut out of or the measure put on the pattern and cut according to the size. and in that case the pattern is used instead of the measure, when the upper for a boot is cut out it is but one piece of leather with a slit at the vamp and a projection for the top of the boot. making but one seam to close and that a circular seam running near the fore part of the boot and ending at the bottom of the counter. Booties cut in the same way or on the same principal only made shorter with a strap behind. And for a laced boot or a laced shoe the uppers are cut similar and left open to be laced, buckled, hooked or buttoned on the side thereof.
